ISOLATING CIRCUIT

Francis A. Wilhelm and Richard D. Milton, Huntsville, Ala., assignors to the United States of America as represented by the Secretary of the Army
Filed Jan. 13, 1964, Ser. No. 337,509
5 Claims. (Cl. 315—171)

The invention described herein may be manufactured and used by or for the Government for governmental purposes without the payment of any royalty thereon.

This invention relates generally to a circuit for isolating a voltage source from a short circuit path. More particularly, the invention relates to a means for isolating and independently controlling the input and output loops of a high-voltage, high-energy circuit with a spark gap.

Three electrode gaps have been used to discharge a previously-charged storage condenser into a fixed load such as an exploding bridgewire by applying a very steep high-voltage pulse to a trigger electrode. In this conventional application of a three-electrode gap the trigger pulse voltage is chosen so that the sum of it and the condenser voltage exceeds the main gap holdoff voltage. The primary objective here is microsecond timing accuracy of the condenser discharge. This application of the three-electrode differs in that the objective is to prevent the load (in this preferred embodiment of the invention being a flash lamp) from being short-circuited by a coil within the generator. Essentially, the spark gap must have two distinct holdoff potentials, one high enough to permit a pre-ionization potential of about 5 kv. to be applied to the flash lamp of a laser device and post-ionization breakdown potential of about 1.5 kv. to permit the generator to discharge into the ionized flash lamp.

Accordingly, it is an object of the present invention to provide an isolating circuit suitable for use in flash lamp circuits.

A further object of the invention is to provide a circuit to prevent a load from being short-circuited by a generator.

A still further object is to provide a circuit with a spark gap means whereby a generator may be permitted to discharge into an ionized flash lamp.

These and other objects and advantages of the present invention will become apparent from the following detailed description and from the accompanying drawing in which:

FIGURE 1 shows a schematic circuit diagram according to a preferred embodiment of the invention;

FIGURE 2 shows a schematic diagram of a portion of a second embodiment of the invention; and

FIGURE 3 illustrates a portion of an additional embodiment of the invention.

Reference numeral 1 denominates a load in the form of a flash lamp which takes 5 kv. to ionize. The flash lamp is part of a laser device, not shown, and supplies power thereto. Connected across the lamp by way of resistor 2 is an ionizing power supply 3. The lamp and the ionizing power supply are connected to a common ground.

A three electrode spark gap device 5 is shown as having main electrodes A and B and a control electrode C. Sparking devices of this kind are commercially available. Electrode B is connected to load 1 by a lead 6. Electrode A is connected to one side of a generator circuit 17 by a lead 8. Electrode C of three electrode spark gap 5 is connected to a switch 9 by way of a resistor 10.

Three electrode spark gap device 5 is of the type which has two distinct holdoff potentials, one between the main

electrodes A and B with no potential supplied to electrode C, and a lower one when there is a potential supplied to electrode C.

Generator 17 consists of a coil 7 having a voltage supply and switching circuit 12 connected in parallel to it. The generator of FIGURE 1 constitutes an induction power supply and has a low internal impedance.

A condenser 18 (FIGURE 2) having voltage charging circuit 19 connected in parallel to it may be substituted for the generator 17 of FIGURE 1. Further, a steady state voltage supply 20 (FIGURE 3) may also be substituted for generator 17 of FIGURE 1.

A potentiometer 13 having slider arm 14 is connected across bias voltage supply 15 by way of the common ground connections. Slider arm 14 of the potentiometer is connected to switch 9.

The sequence of operation is as follows:

(a) Initially the generator is at zero potential and the threshold-control switch 9 is open.

(b) The flash lamp is now ionized by applying a potential of about 5 kv. and, if necessary, a trigger pulse. At this stage the holdoff potential across main electrodes A and B of the spark gap must be above 5 kv. to prevent the generator from shorting the flash lamp through its low impedance to ground.

(c) After the flash lamp ionizes, the potential across the lamp drops to about 1,000 volts. This is due to the voltage drop across resistor 2 when current is being supplied to the ionized flash lamp.

(d) The circuit is now armed by closing switch 9. The breakdown voltage for the control gap (electrodes A and B) is set, either by mechanical choice of the interval or by means of adjusting the bias voltage on electrode C by potentiometer 13. This breakdown voltage is set to a value close to, but greater than, the lamp drop (about 1,000 volts). The lamp is now ready to fire when the generator voltage breaks down the main gap (electrodes A and B).

(e) When the rising generator voltage exceeds the holdoff voltage of the control gap (electrodes A and C), that gap breaks down. The resultant ionization sharply drops the holdoff voltage of the main gap and the generator discharges through the flash lamp. The value of resistor 10 is chosen to insure ionization without significant load-shunting effect.

The above details the sequence when the generator voltages starts from zero, as will happen in the circuit of FIGURE 1. The same circuit can be used to control a voltage source which is a precharged condenser (FIGURE 2) or steady state generator (FIGURE 3) by opening switch 9 to permit ionizing the lamp or lamps, and discharging the voltage source by closing said switch 9.

While the invention has been described with reference to a preferred embodiment thereof, it will be apparent that various modifications and other embodiments thereof will occur to those skilled in the art within the scope of the invention. Accordingly, we desire the scope of our invention to be limited only by the appended claims.

We claim:

- 60 1. An isolating system comprising a first source of voltage having first and second terminals, a lamp having third and fourth terminals, an induction voltage source having fifth and sixth terminals, a three electrode gap means having seventh, eighth, and ninth terminals, means connecting said first, third, and seventh terminals to each other, means connecting the eighth and fifth terminals to one another, further means connecting said second, fourth, and sixth terminals to each other, and a further source of voltage connected between said ninth terminal and said sixth terminal.
- 65 2. An isolating system comprising a first source of volt-

age having first and second terminals, a lamp having third and fourth terminals, a precharged condenser voltage source having fifth and sixth terminals, a three electrode gap means having seventh, eighth, and ninth terminals, means connecting said first, third, and seventh terminals to each other, means connecting the eighth and fifth terminals to one another, further means connecting said second, fourth, and sixth terminals to each other, and a further source of voltage connected between said ninth terminal and said sixth terminal.

3. An isolating system comprising a common lead, a first source of voltage having one side connected to said common lead, and having first connecting means connecting its other side to an output terminal, lamp means connected between said output terminal and the common lead, an induction voltage source, a three-electrode spark gap means having a main gap and a control gap, second connecting means connecting the induction voltage source, the lamp means, and the main gap in a first series circuit,

a source of bias voltage, a switch means, and third connecting means connecting said source of bias voltage, said switch means, said control gap, and said induction voltage source in a second series circuit.

4. A system as set forth in claim 3, wherein said lamp means is a flash lamp of a laser device.

5. A system as set forth in claim 3, wherein said first connecting means is a resistor.
